UNITED STATES PATENT OFFICE.

PETER SORENSEN, OF BROOKLYN, NEW YORK, ASSIGNOR TO JAMES JONES
AND JAMES JONES, JR., OF BROOKLYN, NEW YORK.

ELECTRIC TIME-SWITCH MECHANISM.

SPECIFICATION forming part of Letters Patent No. 691,014, dated January 14, 1902.

Application filed November 6, 1900. Serial No. 35,614. (No model.)

To all whom it may concern.

Be it known that I, PETER SORENSEN, a citizen of the United States, residing in the borough of Brooklyn, city and State of New York, have invented an Improvement in Time Cut-Outs for Electric-Service Systems, of which the following is a specification.

My invention relates to a cut-out device put in operation by a time-operated alarm-release mechanism for automatically breaking or shunting the circuits of electric-service systems at predetermined periods of time.

In carrying out my invention and in combination with a suitable foundation of insulating material and a clock with an alarm-release mechanism I employ a pivoted spring-actuated lever set in operation by the time-piece. A latch holding pivoted switch-bars in engagement with clip-contacts and completing one or more electric circuits is released by the movement of the said pivoted lever, after which spring-operated devices come into action and remove the switch-bars from the clip-contacts to break the circuit or circuits of the service systems, and in so doing the switch-bars are thrown over out of the way. When thus thrown over, the switch-bars may reestablish the circuit through a branch or shunt line by coming into engagement with other clip-contacts in said branch circuit.

In the drawings, Figure 1 is an elevation representing my improvement. Fig. 2 is a vertical section and partial elevation of the same. Fig. 3 is a side elevation of the parts shown in Fig. 2 with the switch-bars thrown over. Fig. 4 is an elevation representing a modification in connection with the switch-bars. Fig. 5 is a side elevation representing a further modification, and Fig. 6 is a diagrammatic view of the circuits employable in connection with the modification Fig. 5.

A represents a foundation, of suitable insulating material, to which the various devices are connected. Usually such foundation has been a slab of marble.

a represents a spring-actuated lever, which is pivoted to the foundation and preferably passes beneath the clock-movement, as shown in Fig. 1. The lever is provided with a spring a^2 for drawing and holding the same in one di-

rection. Said lever preferably comes against a stop 9 (see Fig. 1) to limit the movement in one direction, so as to determine the position of the lever with reference to the arm of the latch device. The upper end of the lever a , behind the clock or timepiece mechanism, is engaged by the alarm-release mechanism, so as to swing the lever on its pivot. Any suitable alarm-release mechanism may be employed for this purpose. I have, however, shown a shaft and rotating arm 1, having a pin thereon adapted to come in contact with and move the lever a , and said lever is partially beneath the clock mechanism, and the lower part thereof extends below the same above the foundation.

I employ switch-bars b , pivotally connected to contact-supports 2 upon the foundation A and provided with binding-posts for the line-wires x . The switch-bars b are connected by a cross-head b' , of insulating material, and said cross-head is provided with a handle b^2 , by which the switch-bars are swung from the dotted position, Fig. 2, into engagement with the latch device, and the outer end of this handle b^2 is preferably made with a rubber buffer to strike against the foundation as the switch is swung over in breaking the circuit. I provide the cross-head b' with a latch-plate 3. 80

c represents a spring-actuated plunger in a case c' , passing through the foundation of insulating material, and d represents a spring-actuated latch device pivoted to the block f , secured to the foundation, and the said latch device is provided with a stop 4 and an arm 5, the outer end of the arm 5 being provided with a roller 7, there being a roller 8 contiguous to the roller 7 and supported in the block f . Clip-contacts e are secured to the foundation of insulating material and provided with binding-posts 6 for the wire which electrically connects the said clip-contacts to one another. In the position shown in Figs. 1 and 2 the switch-bars b are between and in electrical engagement with the clip-contacts e , and the latch-plate 3 of said switch-bars presses against the spring-actuated plunger c to hold the same down in its case, and at the same time the edge of the latch-plate 3 is engaged by the spring-actuated latch device d , and the lower end of the

lever *a* is placed between the rollers 7 and 8 to hold the latch device *d* into engagement with the edge of the latch-plate 3. In this position the circuit is complete, and the spring 5 *a*² holds the lever *a* against the stop 9, with the lower end of the lever between said rollers to fix the position of the latch, this being the normal position of the devices while the current is on and before the current is broken or shunted by the operation of the alarm-release mechanism of the clock. The clock alarm-release is fixed for a predetermined period, and when the time of said period arrives the said mechanism is let off in the usual 15 manner, the arm 1, with its pin, striking the upper end of the lever *a* and swinging the same into the dotted position, Fig. 1. As soon as the lower end of the arm *a* moves out from between the rollers 7 and 8 the spring 20 of the latch device *d* raises the latch, bringing the rollers together and freeing the engagement of the latch with the edge of the latch-plate 3. The moment this latch-plate is freed by the latch device the plunger *c* 25 comes into operation and forces the pivoted switch-bars *b* out of the clip-contacts *e* and the momentum carries the switch-bars over and downward into the dotted position shown in Fig. 2, thus breaking the circuit and either 30 putting out the lights run by the circuit or stopping the mechanical devices operated by the current. To remake the circuit, it is only necessary to return the pivoted switch-bars to the normal position by hand, in doing 35 which the switch-bars pass between the clip-contacts, the plate 3 presses in the spring-actuated plunger, the edge of the latch comes against the stop 4 of the latch-device *d*, swinging the latch device against its spring and 40 bringing the nose thereof over the edge of the plate 3 and opening the space between the rollers 7 and 8, so that the lever *a*, moved by the spring *a*², passes in between the rollers 7 and 8, restoring the normal position of the 45 devices in which the electric circuit is made complete.

In the modification shown in Fig. 4 a wire spring is employed in the form of a loop with coiled ends around a rod 10. This rod 10 50 passes through the contact-support 2, and the doubled part or loop of the wire spring is beneath the switch-bar and the free ends are securely held in any desired manner. This spring is useful to insure the movement of 55 the switch-bars, assisting the spring-actuated plunger in case the same becomes sluggish or more or less inactive in its movements.

In the modification shown in Fig. 5 one or 60 more clip-contacts *e'* are shown secured to the common foundation, and the switch-bar *b* is shown as engaged therewith when in the swung-over position and in which the cross-head *b'* is positively held by a spring-actuated latch *h*. Fig. 6 is a diagram illustrating this modification and suitable circuit connections therefor, the object being to reestablish the circuit in the line-wires *x* & *x*' through

a shunt-line 11 and the clip-contacts *e'* when the switch-bars *b* are disengaged from the clip-contacts *e* and are in engagement with the clip-contacts *e'* and the circuit going to the lamp *i* or other electric-service system is broken.

My invention is applicable for breaking or shunting electric circuits in electric-light or other electric-service systems either for the purpose of putting out the lights at a predetermined period or shutting off the current from machinery, the idea being to control the electric service for lights or machinery in connection with stores, hotels, flats, or other places where electricity is employed for lights or power, so that the vendor of the electricity can control the use and prevent the abuse of the service by the customer. 85

I claim as my invention—

1. In a time cut-out for electric-service systems, the combination with a timepiece and alarm-release mechanism adapted to be set at predetermined periods, of a pivoted lever operated by such mechanism, a pivoted switch, an electric circuit made by the switch in one position and broken by the switch in its opposite position, a latch held in position by the aforesaid lever for engaging the switch and a spring-actuated device for swinging the switch when released by the latch to break the circuit, substantially as set forth. 90

2. In a time cut-out for electric-service systems, the combination with a timepiece and alarm-release mechanism adapted to be set at predetermined periods, of a pivoted lever, a spring and stop for holding the lever in one direction, means connected with the alarm-release for moving the lever in the opposite direction, pivoted switch-bars, electric connections to the pivoted end of the switch-bars, and clip-contacts engaged by the switch-bars in one position, a latch device engaging the pivoted switch-bars and means for holding the latch in engagement with the switch-bars by the lower end of the said lever, and a spring-actuated plunger bearing upon the pivoted switch-bars for forcing the same out of the clip-contacts when released by the latch upon the swinging of said lever, substantially as set forth. 115

3. In a time cut-out for electric-service systems, the combination with a timepiece and alarm-release mechanism, adapted to be set at predetermined periods, of a pivoted lever, a spring and stop for holding the lever in one direction, means connected with the alarm-release for moving the lever in the opposite direction, pivoted switch-bars and a cross-head of insulating material connecting the same at one end, a latch-plate and a handle connected to the cross-head, contact-supports at the pivoted end of said switch-bars and electrical contacts thereto, clip-contacts and electrical connections between the same engaging the said switch-bars, a spring-actuated latch device engaging the latch-plate of the switch-bars and held in engagement by 125 130

the interposition of the lower end of the aforesaid lever, and a spring-actuated plunger for forcing outward the pivoted switch-bars when released by the latch to disconnect the same 5 from the clip-contacts, substantially as set forth.

4. In a time cut-out for electric-service systems, the combination with a timepiece and alarm-release mechanism adapted to be set at 10 predetermined periods, of a pivoted lever, a spring and stop for holding the lever in one direction, means connected with the alarm-release for moving the lever in the opposite direction, pivoted switch-bars and a cross-head 15 of insulating material connecting the same, a handle and a latch-plate connected to said cross-head, contact-supports to which said switch-bars are pivoted and electrical connections thereto, clip-contacts electrically 20 connected and engaged by the switch-bars, a spring-actuated latch device pivoted to the block of insulating material and having a stop 4 and an arm 5 between which arm 5 and block of insulating material the lower end of 25 the aforesaid pivoted lever is interposed to hold the latch in engagement with the latch-plate, and a spring-actuated plunger bearing upon the latch-plate and adapted to force the pivoted switch-bars out of engagement with 30 the clip-contacts when released by the latch device, substantially as set forth.

5. In a time cut-out for electric-service systems, the combination with a timepiece and alarm-release mechanism adapted to be set at 35 predetermined periods, of a pivoted lever, a spring and stop for holding the lever in one direction, means connected with the alarm-release for moving the lever in the opposite direction, a pair of pivoted switch-bars, a cross- 40 head of insulating material connecting the same, a handle and a latch-plate connected to

said cross-head, contact-supports to which said switch-bars are pivoted, and electrical connections thereto, clip-contacts electrically connected and engaged by the switch-bars, a 45 spring-actuated latch device pivoted to the block of insulating material and having a stop 4 and an arm 5 between which arm 5 and block of insulating material the lower end of the aforesaid pivoted lever is interposed to hold the latch in engagement with the latch-plate, a roller 7 upon the free end of the arm 5 and a roller 8 in the block of insulating material in proximity thereto, and between which rollers the lower end of the arm 5 is 55 interposed, and a spring-actuated plunger bearing upon the latch-plate and adapted to force the pivoted switch-bars out of engagement with the clip-contacts when released by the latch device, substantially as set forth. 60

6. In a time cut-out for electric-service systems, the combination with a timepiece and alarm-release mechanism adapted to be set at predetermined periods, of a pivoted lever operated by such mechanism, a pivoted switch, 65 an electric circuit made by the switch in one position and broken by the switch in its opposite position, a latch for engaging the switch held in position by the aforesaid lever and a spring-actuated device for swinging the lever 70 when released by the latch to break the circuit, clip-contacts engaged by the pivoted switch in its swung-over position, a latch for holding the switch and a shunt-circuit made by the switch in this latter position, substantially as specified. 75

Signed by me this 31st day of October, 1900.

PETER SORENSEN.
